UNITED STATES PATENT OFFICE.

ALLEN E. OSTRANDER, OF RIDGEWOOD, NEW JERSEY, AND AUGUST G. SANDMAN, OF BALTIMORE, MARYLAND, ASSIGNEES TO AMERICAN CAR & FOUNDRY COMPANY, OF NEW YORK, N. Y., A CORPORATION OF NEW JERSEY.

CAR ROOF.

Application filed November 19, 1921. Serial No. 516,373.

To all whom it may concern:

Be it known that we, ALLEN E. OSTRANDER and AUGUST G. SANDMAN, residing at Ridgewood, county of Bergen, and State of New Jersey, and Baltimore, State of Maryland, respectively, and being citizens of the United States, have invented certain new and useful Improvements in a Car Roof, of which the following is a full, clear, and exact description, such as will enable others skilled in the art to which it appertains to make and to use the same, reference being had to the accompanying drawings, which illustrate the preferred form of the invention, though it is to be understood that the invention is not limited to the exact details of construction shown and described, as it is obvious that various modifications thereof within the scope of the claims will occur to persons skilled in the art.

In said drawings:

Fig. 1 is a vertical sectional view taken on line 1—1 of Fig. 2, and looking in the direction indicated by the arrow and illustrating one embodiment of our means for securing outside roof boards of car roofs;

Fig. 2 is a similar view taken on line 2—2 of Fig. 1, looking in the direction indicated by the arrow;

Fig. 3 is a plan view of a portion of the roof board fastening means; and

Fig. 4 is a view similar to Fig. 1, illustrating a modified form of our invention.

One object of our invention is to provide means for positively holding outside roof boards of car roofs to the car framing.

Another object is to secure outside roof boards of car roofs in which inside metal roofs are employed.

A still further object is to provide securing means for outside roof boards of railway cars supplementing other and commonly used fastening devices.

In the drawings, 1 represents one of the two side plates of the car framing, 2 the outside sheathing, and 3 represents one of the several carlines positioned on the side plates at fixed points throughout the length of the car. Resting upon the side plates 1 and upon the usual intermediate purlines (not shown) are metal roof sheets 4 flanged downwardly over the outside sheathing and provided with upstanding flanged side

flanges 5 overlying super-carlines 6 positioned between the roof sheets. Fitted over said super-carlines and roof-sheet flanges 5 are the usual metal caps 7 to prevent the entrance of water to the car interior.

Upon the roof-sheets 4 and above the side plates 1 and intermediate purlines are super-purlines 8 securely fastened to the side plates and intermediate purlines and to the super-carlines 6 in any desired manner. Upon said super-purlines 8 are secured the usual outside roof-boards 9 commonly secured to the underlying framing members by means of nails or the like and extending over the car sides.

The construction so far described is typical of outside wood roof designs commonly used and in which inside metal roofs are employed to render the roof structure watertight. In transit, car frames have a tendency to weave because of the failure of the means relied upon to hold the several members of the car structure together. This weaving tendency is always more pronounced at the joints between the car framing members proper and the roof boards. The roof boards become disjointed and wrenched from their positions in the structure due to the failure of the fastening means under the racking strains of service, and are frequently blown off and lost when thus exposed to the action of the elements.

To insure positive anchorage for outside roof-boards applied as above outlined and to supplement the fastening means heretofore employed in roofs of the character above described, underlying metallic eaves boards or fascia plates 10 are secured to the car side. The roof-boards 9 are secured to outwardly extending stiffening flanges 11 on said fascia plates 10 by means of flexible rods or lengths of wire 12, said wire interlacing the roof boards 9 and fascia plates 10 and firmly and positively securing said roof boards to the car framing. For convenience in handling, the wires are cut into lengths which are best adapted for threading same through registered openings 13 and 14 in the roof boards and fascia plates, respectively. The terminals of each length of wire may be secured to adjacent roof-boards 9 by means of staples 15 or the like, and at the ends of the car the wire terminals may lap past each

other and be folded about the outer edges of the end roof-boards, as shown in Figs. 1 and 3, and secured as described.

The fascia plates 10 are secured to the car frame by means of bolts 16 or the like positioned at suitable points along the lower margins of said plates and extending through said plates, the side plates 1, and outside sheathing 2. If desired, additional securing means 17, shown as anchor bolts, may be employed to further insure sufficient connection between the car framing and the roof-boards 9 wire-bound to flanges 11 on said fascia plates. Such additional means may extend through the fascia plates and engage adjacent super-purlines 8, as indicated in the drawings. The lower margins of fascia plates 10 are spaced from the car side and preferably held in such position by means of thimbles 18 mounted upon bolts 16, to permit any water finding its way through the board roof to the inner roofing sheets 4 to be drained off through the openings thus provided. The lower margin may be flanged outwardly as shown at 19 to provide a watershed to keep water driven against said fascia plates from running down the car side and to further stiffen the fascia plates. Within the scope of our invention the design may be modified to use a series of intermitted rods or wires 12^a overlying spaced portions only of the board roof instead of the unbroken lines of contact obtained with the binding elements arranged as above described. In the design as modified, the elimination of securing staples 15 is contemplated, and the binding rods 12^a should be of heavier gauge wire than required in the other embodiment and have their terminal portions extending downwardly through both roof boards 9 and securing flanges 11 of the fascia plates 10 and there held by bending said downwardly extending terminal portions to engage the underside of flanges 11 as indicated at 20. Thus arranged, the separated rods 12^a are held in a fixed spaced relation through the medium of the fascia plates 10 connecting said spaced rods, the whole combining to restrain movement of the roof-boards longitudinally of the car.

With the roof-boards bound to the car framing as stated, they are readily removable for repair or replacement and pos-

tively and securely held to the car framing throughout the length of the car, reducing maintenance cost to a minimum.

What we claim is:

1. In a railway car having an outer board roof, flanged fascia plates secured to the car side adjacent said roof, and flexible means threaded through said board roof and the flanges of the fascia plates. 60
2. In a car having a board roof and flanged metallic fascia plates, and flexible binding means interlacing said board roof and the flanges of said fascia plates. 65
3. In a car having an outer board roof and inner metallic roof, metallic fascia plates spaced from said inner roof and underlying said board roof, and flexible binding means interlacing said board roof and the flanges of the fascia plates. 70
4. In a railway car having a roof comprising boards extending over the car-sides, flanged fascia plates underlying said roof boards, and flexible binding means connecting said roof boards together and to the flanges of said fascia plates. 75
5. In a car roof construction, the combination comprising car framing members extending transversely and longitudinally of said roof, flanged fascia plates secured to said framing members, roof boards arranged transversely of the car and overlying said framing members and fascia plates, and flexible binding means overlying said roof boards and engaging with the flanges of said fascia plates. 80
6. In a car having an outer board roof and inner metallic roof, metallic fascia plates spaced from said inner roof and underlying said board roof, and flexible binding means securing said board roof to said fascia plates. 85
7. In railway car construction, outer roof boards extending outwardly from the car side, an outwardly flanged metallic fascia plate extending longitudinally of the car side and positioned with a flange underlying said roof boards, and flexible binding means combining with said flange of the fascia plate to restrain movement of said roof boards longitudinally of the car. 100

In witness whereof we have hereunto set our hands.

ALLEN E. OSTRANDER.
AUGUST G. SANDMAN.
